INCUBATING APPARATUS

Samuel H. Smith, Cleveland, Ohio, assignor, by
mesne assignments, to The Trescott Company,
Fairport, N. Y., a corporation of New York.

Application July 17, 1948, Serial No. 39,303

6 Claims. (Cl. 119—44)

1

The present invention relates generally to egg incubators and more particularly to a novel and very useful incubator, and hatcher, including egg carrying trays and egg-tilting mechanisms of unique design and operation and new temperature and humidity control systems enabling automatic sharp control over incubating conditions at all times.

In accordance with this invention, which is predicated upon my surprising discovery, subsequently to be described, it is now possible to overcome many difficulties and shortcomings of the prior art and to provide egg incubating and hatching means which are not only very economical to manufacture and install and service, but are also capable of consistently producing better results than the incubators heretofore known. My said discovery is that it is not necessary to tilt the egg-carrying trays themselves to obtain the necessary movement of eggs during incubation, and that fully adequate motion can be imparted to the eggs through the substantially horizontal, reciprocating movement of trays of certain particular and novel form and type throughout a distance of about only two inches. These trays include rotatable egg-supporting elements which are spaced apart a predetermined distance for rotation simultaneously about spaced axes as the trays are moved relative to a fixed supporting structure, frictionally engaged or associated with said rotatable elements. I have further found that by using a plurality of such trays arranged in several vertical tiers and spacing the trays apart to a small but critical extent, and by providing means for blowing air to be circulated through the incubator in a certain manner and providing for the flow of other air between and through the trays in a certain manner, all the eggs of a given charge may be subjected to the same ideal temperature (99°F.) within approximately one-tenth of a degree during the entire incubation period. This result is obtained without providing the central passageway common in the prior art, and consequently the present incubators have substantially greater production capacity per unit of volume and floor space than those hitherto in general use. Also, in accordance with this invention, a single blower will suffice to accomplish the foregoing result where a plurality of blowers were necessarily employed for the purpose heretofore.

Furthermore, according to the present invention, humidity control is accomplished through new and very effective means which has the additional and unexpected effect of rapidly collecting and automatically disposing of substantially all the down evolving from freshly hatched chicks, thereby overcoming a maintenance problem which has never heretofore been satisfactorily solved to my knowledge. The automatic control elements for both temperature and hu-

2

midity control systems, moreover, are to the best of my knowledge, novel and are unquestionably superior in their control effect to any known before.

As a still further advantage of the present device, attributable to the aforementioned surprising discovery and to the novel egg-carrying trays of this invention, the yield and quality of chicks is materially improved over the prior art devices as through the novel combination of elements used in the hatching and the novel hatching systems which automatically results in the separation of the freshly hatched chicks from the unhatched and hatching chicks. Because of this feature, chicks which would otherwise be injured or killed in attempting to emerge from and shed their shells, after most of the others have hatched, will be free and unimpaired in their struggles and will have every opportunity to hatch successfully. In prior art incubators the difficulties of hatching increased with the emergence of each chick from his shell due to the corresponding decrease in space in the egg trays.

Those skilled in the art will gain a better understanding of the apparatus of the present invention from the following detailed description of the invention in a preferred form, reference being had to the drawings accompanying and forming a part of this specification, in which:

Figure 1 is a longitudinal, vertical, sectional view of an incubator of this invention;

Figure 2 is a side elevational view of a tray supporting and moving structure of my invention for use in the shell of Fig. 1, showing in a cross-section an egg-carrying tray and a hatching tray in their customary hatching-period position;

Figure 3 is an enlarged fragmentary plan view of an egg-carrying tray of the present invention;

Figure 4 is an enlarged fragmentary, sectional view taken on line 4—4 of Fig. 3 and showing how eggs are disposed in and carried by the tray;

Figure 5 is an enlarged fragmentary, sectional view taken on line 5—5 of Fig. 3;

Figure 6 is a view similar to that of Fig. 4, showing the tray in fully advanced position and indicating the motion of the eggs resulting from shifting the tray from the Fig. 4 position to the Fig. 6 position;

Figure 7 is a fragmentary, perspective view of one of the track brackets of the tray of Fig. 3;

Figure 8 is a wiring diagram of the temperature and humidity control circuits of the present invention, showing the temperature sensitive elements within the incubator indicated in outline;

Figure 9 is a fragmentary, side elevational view of a sheet metal blank from which the sides and end portions of the tray of Fig. 3 are constructed, the sections along which the blank is folded in the transformation being shown in phantom;

Figure 10 is an enlarged perspective view of a portion of a tray of this invention; and

Fig. 11 is a perspective view of a typical drop latch, supporting structure therefor being shown fragmentarily.

With regard to Figs. 1 and 2, the incubator shell S is compact, sturdy and well insulated and yet is easily accessible from either end for loading and unloading operations and maintenance and repair attentions. Generally speaking, it is rectangular and made up of bottom wall 10, top wall 11, opposing side walls, a loading end wall 14 including a hinged door 15, and a hatching or unloading end wall 17 largely consisting of a door 19 also hinged at one side to one of the four corner columns of the shell. Extending transversely of the shell and defining the floor thereof are three abutting metal channels 20 with their sides disposed downwardly. The outer sides 21 of the two end channels are secured to metal box sections 22 which rest on metal supporting skids 23 on which shell S may be moved about. Wooden blocks 24 are employed in joining in spaced relation the metal parts of box sections 22 and channels 20 to minimize heat transfer between these parts. Suitable heat insulating material 25, such as Celotex is packed in the channels and held in place by wooden panels 27 engaging the channel sides and closing the ends thereof. The top wall and side walls are each similarly constructed of three abutting metal channels 26 and box sections as indicated at 28, which are secured to the channel assemblies in insulating relation by means of the wooden blocks 29, as described above. Celotex or equivalent insulating material 30 is packed in channels 26 and light metal sheeting 31 closes said channels and retains the insulation 30 in place.

The end walls are quite different from the others but are quite similar to each other, comprising in each instance an upper panel 33 of wood (one shown) which is secured to the top wall by suitable means such as screws 34 and to a transversely extending beam 35 disposed a short distance below the top wall. Doors 15 and 19 which extend from just below said panels to a point below the upper edge of bottom wall 10 and from one side of shell S to the other, constitute the remainder of these end walls. Each of these doors comprises a pan 37 of relatively thin metal having a wooden cover plate 38 secured thereto and defining a space within the pan and heat insulating material 39 disposed in this space. Attachment of the door to shell S may be accomplished by conventional means such as hinges and clamps, rubber sealers 40 being attached to the inner peripheral portions of the doors for air tightness.

The tray-supporting structure T, as shown in Fig. 2, comprises two lattice-like assemblies (one being shown), each of which comprises six sheet metal columns 45 and eighteen angle iron beams 46 (three not shown) substantially equally spaced and extending horizontally across the area defined by columns 45 to which they are secured by means of spot welds. On the upper surfaces of their horizontally extending portions beams 46 are provided with prominences or ridges 47 located in a particular manner for a purpose subsequently to be described. These assemblies are disposed in register with each other adjacent to the side walls of the incubator, being hung on flanged hanger irons 48 to shell S by top beam members 49 which have flanged portions in sup-

porting engagement with hangers 48. In the upper part of the hatching section of structure T, a relatively short angle iron beam 51 for carrying a horizontally disposed plate 52 is secured in position by welds to a column 45 and a short column element 54. The purpose of plate 52 is to prevent the escape of chicks from the uppermost egg-carrying tray shown immediately therebelow. Still another angle iron beam 55 twice as long as beam 51 is disposed at the bottom of the hatching section, joining the end and the adjacent column 45 to support a hatching tray below the lowermost egg-carrying tray.

The tray-moving and egg-tilting mechanism 15 M comprises in general an assembly defining in side elevation a pair of parallelograms having a common horizontal side and having generally vertical sides pivoted in their mid-sections and at their ends for motion relative to the horizontal parallel sides and to each other. This assembly, except for actuating means and tray-engaging elements, is located back of structure T and between said structure and the adjacent side wall of shell S. The actuating means includes 25 a hydraulic piston cylinder 60 operatively associated with both mechanisms M through pivoted links 61 (one shown) connected to the upper horizontal member 62 of each said mechanism for reciprocating movement thereof at predetermined regular intervals. Analyzing the structure more in detail, it is seen that in each case the moving mechanism, in addition to the foregoing elements includes a lower horizontally disposed angle iron member 64 which extends from 30 adjacent to the loading end of structure T to a point adjacent to the hatching end thereof. Horizontal members 62 and 64 are connected by means of two parallel upper links 66 pivoted at their upper ends to member 62 adjacent to its 35 ends and pivoted in the mid-sections to the supporting structure T, and by means of two parallel lower levers 67 which are similarly associated with and connected to the supporting structure and member 64. The free ends of 40 links 66 and 67 are pivoted together, as indicated in Fig. 2. Three columns 70 comprising metal plates are welded at their ends to members 62 and 64 and provided with drop latches 72 for 45 engaging egg-carrying trays supported on beams 46. Latches 72 of the two columns nearest the loading end are disposed apart in every case the width of an egg-carrying tray, while those of the third column are disposed apart from those of the intermediate column a distance equal to 50 the width of two such trays. Columns 70 are all joined together by means of four horizontal bars or rods 73 equally spaced apart to assure the transfer of moving effort substantially equally from piston cylinder 60 throughout structure 55 M to the egg-carrying trays themselves.

Latches 72 are each of two-piece construction comprising an angle iron 74 welded to column 70 and provided with two spaced slots in its horizontally extending portion, and a drop element 65 in the form of bar or rod 75 having end portions which extend through the bracket slots and having a mid section suspended below the horizontal portion of bracket 74 for engagement with the end of an egg tray. Element 75 is in effect a ratchet, being readily passed by a tray moving from right to left in respect to the latch shown in Fig. 11 and being effective to position the tray when it is moved from right to left against the tray. By virtue of the manner in 70 75 which the latches are mounted on the columns

of the egg moving frame, as indicated in Fig. 1, a tray placed in the loading end of an incubator is readily slipped toward the central portion of the machine past the first and second drop latches until it engages the third drop latch which opposes the first two drop latches and stops the tray just short of the hatching compartment. Thus, a total of three trays can be loaded in tandem in the machine and gripped between a first and a third drop latch whereby all three trays will be moved lengthwise of the machine when the tray moving mechanism is actuated in either direction. When a tray is to be removed to the hatching compartment of the machine, the third drop latch or latches engaging it are manually lifted to release the tray and then dropped for engagement with the next tray in sequence.

Referring now to Fig. 3, the egg-carrying trays E of the present invention in general comprise a frame means F, and a plurality of egg-supporting means R associated with the frame means for rotation about spaced axes. More in detail, however, in these trays the frame means includes sheet metal sides 78 and ends 79, preferably of unitary construction, and brackets 80 which are movable with respect to the frames and attached to end portions 79. Brackets 80 define below said frame ends a track 81 upon which wheels 85 may be run, and these ends are apertured as at 83 to receive rods R which extend lengthwise of the frames and have secured to their ends or within the ends 79 discs or wheels 85 to run on tracks 81. The spacing between these rods is such that eggs of average size may be supported thereon and when the rods are rotated relatively to the eggs, as by moving the rest of the tray relative to tracks 81, the eggs will be moved from a position such as indicated at Fig. 4 to that shown in Fig. 6, where the major axes of the eggs are generally parallel to each other and all are disposed at an angle of approximately 30° to the vertical. It will be appreciated that such movement from one extreme position of the track to the other will result in a total movement of a given egg on its major axis through approximately 60°. Surprisingly enough, however, in addition to this effect the eggs all tend to rotate to an appreciable extent at the same time. This combined and complex motion is of beneficial effect and I hypothesize, without imposing limitations on the appended claims but merely in the interest of complete exposition of my invention, that for the same results less tilting is necessary where this novel motion obtains than where it doesn't.

Brackets 80 are each provided with a pair of hanger clips 86 at their upper ends which grip the upper edge portion of an end 79 to support the track against the discs 85 and to engage sides 78 and limit motion of tray F relative to the track to a predetermined maximum. By virtue of the manner in which rods R and brackets 80 are arranged and associated, the tray is supported by means of the rods and brackets on beams 46, tracks 81 resting thereon and being retained in position by ridges 47 as the trays are moved by mechanism M. Two spacer brackets or lugs 88 are attached to the frame, one being located on each side thereof for engagement with one of the two outer rods R to prevent these rods from moving laterally relative to the other rods under the weight of eggs on the tray.

From the foregoing description of tray F, it is seen that the manufacture thereof as a unitary structure insofar as the side and end elements 75

are concerned can be carried out simply and easily on a mass production basis, starting with a piece of sheet metal of the desired dimensions and blanking it, as shown in Figs. 9. In this practice the blank may be folded along the horizontally extending phantom lines of Fig. 9 to produce the box shape illustrated at X in Figs. 4, 5, 6 and 10, and then welded at spots along opposing engaging portions as necessary to produce a rigid construction, the rods R having previously been inserted in the assembly with discs 85 welded thereto. Finally, the track brackets 80 are hung upon the ends of the tray and secured movably in place by means of their hanger clips 86.

The temperature and humidity control system is diagrammatically shown in Fig. 8 and comprises two separate thyratron circuits, one of which includes a dry bulb temperature-sensitive element A which has a negative temperature coefficient, and the other of which includes a wet bulb element B of the same temperature-electrical characteristics as element A. In the circuit of element A an electrical heating element 90 is controlled by a solenoid 91, 60-cycle alternating current being supplied at 115 volts by a line 92 leading to a transformer 93 having two 250-volt secondary elements 95 and a secondary 6.3-volt coil 96 serving filament 98 of thyratron tube 99. The 250-volt elements are center-tapped and connected through a potentiometer 100 to the element A, while the plate of the thyratron tube is connected to the line through solenoid 91 and the grids of the tube are electrically associated with the potentiometer through a pair of resistors 102 for current flow control. A ballast tube 105 is arranged in series with transformer 93 for voltage regulation, and a variable resistor 106 for rough ranging adjustment on potentiometer 100 is situated in series with said potentiometer.

The second circuit concerns the humidity control and is of the same basic design as the first and operates on the same principle, but with a different effect, as those skilled in the art will understand.

In the operation of the circuit A, adjustment is made at the control temperature so that the grid lead from tube 99 is at the proper voltage just to cut off the tube at the predetermined temperature. Thus, as the temperature within the incubator (indicated at 110 in dotted outline) increases, element A decreases its resistance and thus makes the grid more negative, finally resulting in circuit breakage and de-energizing of solenoid 91. The reverse effect is obtained when the heating element is again supplied with current, when the temperature falls and the circuit is closed by the solenoid being actuated through the action of the thyratron tube. The circuit including element B operates in exactly the same manner, of course, and may be set in the same way, except that the reference there is to the humidity or wet bulb temperature rather than the dry bulb temperature as in element A.

These control systems are located in shell S, being enclosed in a cabinet or housing indicated at 111 just inside hatching end wall 117 and above door 119.

The humidifier element 112 of the present invention, as shown in Fig. 1, comprises a metal pan 113 inclined downwardly at a small angle in the direction of the hatching end of the incubator and disposed above the tray chamber in a duct 114 extending lengthwise of shell S.

and having an air inlet opening 115 adjacent to and below the lower end of humidifier 112 and an outlet 116 directly beneath an inverted fan 118 located just inside the hatching end of said shell. The pan carries a screen 119 for uniformly distributing water flowing onto the pan from a delivery line 120 entering the top of shell S, and water flowing from the pan is drawn off outside the incubator through a line 122. The heating element 90 may be associated with the humidifier so that heat may be delivered rapidly and effectively to water flowing over the pan to further increase its rate of evaporation. Water flowing over this pan during each hatching period will sequester down evolved from chicks and carried by air currents into duct 114, thus eliminating the necessity of the special down-collecting air filters of hitherto conventional incubators.

In the use of an incubator of the design hereinabove described, it has been found advantageous to follow a certain definite schedule and to proceed in the manner hereinbelow outlined with the humidity and temperature controls set and the incubator at predetermined wet and dry bulb temperatures. Trays F, as shown in Fig. 3, are loaded with eggs, as indicated in Figs. 4 and 6, and placed in the first compartment of the incubator chamber between the first and second columns of the vertical tiers and on odd shelves, beginning with the top shelf. The trays extend from adjacent one wall to adjacent the opposite wall and rest on their track brackets 89 upon the beams 46, and are engaged by latches 72 of mechanism M whereby the trays are moved periodically relative to structure T and the track brackets, with the result that the eggs are tilted, as described above. Assuming that the first series of trays is placed in the incubator on Sunday, a second group may be made up in the same manner and loaded in the even-number spaces on Wednesday, whereupon the odd-number trays will be moved into the second section of the incubating compartment and the cycle will be repeated upon the following Sunday with the even-number trays moving into the second position of the incubating section and new trays coming into odd-number spaces of the first section. On the eighteenth day after being placed in the incubator, the first trays are moved into the hatching section as indicated in Fig. 2; and hatching trays 125, comprising open pans substantially deeper than the egg-carrying trays and having imperforate bottoms, are placed under each egg-carrying tray and receive the chicks as they hatch and fall between rods R. After a total of twenty-one and one-half days in the incubator, the eggs of the odd-number trays will have hatched and may be removed together with the hatching trays containing the chicks, and another new series started through the incubator.

So that the moving mechanism will have a positive effect at all times upon the trays regardless of the direction of their movement relative to the supporting structure, empty trays are carried along with full trays until the hatching cycle is brought up to the point where all the trays moving through the structure contain eggs. In other words, referring to the first step in starting the incubator as described above, it is necessary first to load two empty trays into the second and final sections of the incubator chamber in order that the egg-carrying tray loaded into the first section will be returned to its original position when the moving mechanism oper-

ates on its return stroke. Likewise and for the same reason, when the incubator is to be shut down, empty trays E are carried through with full trays until the latter are through the incubating and hatching periods and withdrawn from shell S.

Air circulation in the incubator is continuous throughout the period that the incubator is in use so that all the eggs and chicks therein will be subjected to only the most ideal temperature and humidity conditions at all times. As indicated by the arrows in Fig. 1, air flow within the incubator is directly downward from fan 118 in a main stream through outlet 116 and thence longitudinally of shell S in a plurality of streams between the horizontal rows of trays E. At the hatching end of the shell the various streams unite and flow upwardly and enter duct 114 through opening 115, wherein flow again is generally horizontal or longitudinal of the shell, a portion of the air flowing over and another portion of it flowing under pan 113 to the fan. By means of an opening (not shown) in the top of shell S a small portion of the circulating air may be vented continuously and by other similar means (also not shown) fresh air make-up may be drawn into said shell.

From the above description of the incubator and hatcher of the present invention and particularly the portion thereof relating to my present novel egg-carrying trays and egg-tilting mechanisms, it will be understood that generally the novel method of this invention comprises the steps of turning an egg on its major axis and simultaneously turning the egg on its minor axis during its incubation period for the purpose of preventing attachment of the chick embryo to the shell. More specifically, in the preferred practice of this method the egg is placed substantially on end with the small end thereof directed generally downwardly as indicated in Fig. 4. In this position the major axis of the egg is directed generally vertically, while the minor axis extends generally horizontally. Periodically the egg is moved from one tilted position to another and simultaneously is turned on its major axis as mentioned above. Actually this movement is one which results in the major axis travelling through a vertical angle approximating 60° and is reciprocal so that at timed intervals the upper end of the egg's major axis describes a substantially vertical arc of approximately 60° as it travels from a position substantially 30° to the vertical to another position approximately 30° on the other side of the vertical. This turning motion may involve a complete revolution or several revolutions of the egg in each of the reciprocating strokes, but preferably it is limited to less than about 180° and in the best practice is about 45°, since this turning motion to a greater extent is not necessary, particularly where the tilting motion of the egg is as described above. In commercial operations in accordance with the present method a plurality of eggs will be moved at the same time to approximately the same extent as, for instance, where they are loaded into a tray of the type shown in Fig. 3 so that at least all of those in one group or, in other words, in one tray will be moved simultaneously.

From the foregoing description and the accompanying drawings those skilled in the art will understand that, unlike the incubators known and used heretofore, that of my present invention is readily adaptable to very economical mass production methods. Furthermore, the ma-

terials involved in its construction are of standard specifications and readily available at relatively low cost so that the total cost of manufacture is substantially less than that of any other incubator of equivalent capacity.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of this invention as claimed herein.

Having thus described the present invention so that those skilled in the art will be able to understand and practice the same, I state that what I desire to secure by Letters Patent is defined in what is claimed.

What is claimed is:

1. An incubator comprising a housing for a plurality of egg trays, and means within the housing for reciprocally moving the trays substantially horizontally and tilting eggs carried thereby, said means comprising a frame movable relative to said housing and engaging said trays, and actuating mechanism supported by the housing and connected to the frame for causing reciprocating movement of said frame, said frame comprising substantially horizontally disposed elongated members, spaced vertically disposed elongated members connected to said horizontal members, latch means carried by vertical members for engagement with the trays to move the trays with the frame relative to the housing, and links pivotally secured to the housing and to the frame to move the frame and to guide said frame in motion relative to the housing.

2. An incubator comprising a housing for a plurality of egg trays, and means within the housing for reciprocally moving the trays substantially horizontally and tilting eggs carried thereby, said means comprising a frame reciprocably associated with said housing and engaging said trays, and a hydraulic piston cylinder operatively associated with said frame for causing reciprocating movement of said frame, said frame comprising substantially horizontally disposed elongated members, spaced vertically disposed elongated members connected to said horizontal members, latch means carried by vertical members for engagement with the trays to move the trays with the frame relative to the housing, and links pivotally secured to the housing and to the frame to move the frame and to guide said frame in motion relative to the housing, and said piston cylinder being vertically spaced from the frame and the piston being connected to one of said horizontally disposed frame members for reciprocating motion therewith.

3. An incubator comprising a housing for a plurality of egg trays, and means within the housing for reciprocally moving the trays substantially horizontally and tilting eggs carried thereby, said means comprising a frame having substantially parallel and horizontally top and bottom members, two pair of links pivoted to the top and bottom members at spaced locations, each link being pivotally connected at its mid-section to the housing, a plurality of vertically extending tray-engaging members connected to said top and bottom members for movement therewith, and a hydraulic piston cylinder connected to the frame for moving it reciprocally.

4. An incubator comprising a housing for a

plurality of egg trays, and means within the housing for reciprocally moving the trays substantially horizontally and tilting eggs carried thereby, said means comprising a pair of spaced

5 apart frames each having substantially parallel and horizontal top and bottom members, two pair of links pivoted to the top and bottom members at spaced locations, each link being pivotally connected at its mid-section to the housing, a 10 pair of vertically extending tray-engaging members connected to said top and bottom members for movement therewith, and a hydraulic piston cylinder operatively associated with said frames for moving them reciprocally in phase.

15 5. In an incubator including a housing and a plurality of horizontally disposed, open top, egg-carrying trays arranged one above another and supported within the housing for motion relative to said housing, the combination of a frame in 20 the housing movable relative to the housing and engaging the trays, said frame comprising a plurality of spaced, horizontally disposed elongated members, spaced vertically disposed elongated members connected to the horizontal members for movement therewith, means carried by the frame to engage the trays, and links pivotally secured to the housing and to the said horizontal members to guide the frame in motion relative to the housing.

25 6. In an incubator including a housing and a plurality of horizontally disposed, open top, egg-carrying trays arranged one above another and supported within the housing for motion relative to said housing, the combination of a frame in 30 the housing movable relative to the housing and engaging the trays, said frame comprising a plurality of spaced, horizontally disposed elongated members, spaced vertically disposed elongated members connected to the horizontal members for movement therewith, latch means carried by the frame to engage the trays, and links pivotally secured to the housing and to the said horizontal members to guide the frame in motion relative to the housing, said latch means comprising drop-latches secured to the said vertical members for movement therewith to engage the trays and reciprocate them relative to the housing and for motion relative to the trays at predetermined intervals preparatory to advancing 35 the trays toward the discharge end of the housing.
